LOADING COIL

Application filed May 14, 1930, Serial No. 452,492, and in Germany May 27, 1929.

The usual loading coils for transmission lines contain two windings, one of which is connected in the outgoing conductor and the other in the return conductor of a circuit. In such a case, extremely high demands are put on the symmetry of the coils, that is, on the exact similarity of the electrical properties of the two windings.

From other apparatus, for instance, telephone transformers, a simple means is known for obtaining such symmetry to a very high degree. For this purpose, the two windings are made by winding two wires bifilarly together. This means has, however, hitherto not been employed for loading coils and the reason for not doing this is because the very close position of the two wires on the whole of their length causes a high capacity of the two windings in respect to each other. In the case of loading coils, such capacity has been regarded as a drawback, because, as is well known, the purpose of the insertion of loading coils is to compensate for the detrimental influence of capacity on the transmission of the speaking-currents. Consequently a high self-capacity of the coils, would be looked upon as a step in the wrong direction.

The subject of the invention is a loading coil the two halves of the windings of which consist of two wires which are wound bifilarly together, in spite of the above-mentioned considerations. The invention is based on the conception that a line which is provided with such coils possesses a considerable advantage, namely, that the transmission delay for the various frequencies involved is brought more nearly to the same value, whereas the above-described disadvantages can be obviated by correspondingly greater dimensioning of the coils or reduction of the distance between the coils.

It is well known that tendencies to resonant effects in telephone lines lead to "phase distortion", which, in the case of long lines, causes considerable distortion of speech, and, therefore, in the case of long-distance cable-lines, one is forced either to apply particularly weak loading or to avoid phase distortion by special artificial circuits ("phase-compensation"). It is further well known that this

can be obtained, for example, by connecting condensers to the loading coils in a certain manner. According to the present invention the self-capacity of a bifilarly wound loading coil can, with suitable arrangement, be laid or dimensioned in such a way as is required for this purpose, so that the insertion of special condensers is, in general, superfluous.

In the accompanying drawings, Fig. 1 is a diagram showing a known form of connection for phase-compensation; Fig. 2 is a diagram of a winding according to the present invention; and Fig. 3 is an explanatory diagram.

In the case of the well known phase-compensation on the individual loading coils, the two condensers are connected cross-wise between the two windings of a loading coil, as at A₁ B₁ and A₂ B₂ in Fig. 1, and the capacity C of each individual condenser is made from 0.4 to 0.8, of the capacity of a complete coil-section. According to the present invention, the two windings A₁, B₁, and A₂, B₂, are laid bifilarly in the manner shown in Fig. 2 so that the terminals A₁ and B₂ of the outgoing conductor and return conductor respectively, lie on each other, and so also the opposite terminals B₁ and A₂. The system of capacities so produced between the two windings is diagrammatically shown in Fig. 3, in which as in Fig. 1, A₁, B₁, and A₂, B₂, represent the coils in two longitudinal conductors of a physical circuit. Every two points which lie directly on each other in Fig. 2 are represented in Fig. 3 by two points which lie symmetrically with respect to the centre of symmetry O. A₁ B₂ and B₁ A₂ are such pairs, as already indicated. Other pairs are represented by E₁ F₂, D₁ D₂, F₁ E₂. If the two elements of length d_{s1} and d_{s2} are regarded in close proximity of E₁ or F₂, then the differential capacity dC lies between the two. The same differential capacity lies between equally large elements of length in the neighborhood of other symmetrical pairs of points.

The bifilar winding can, for example, be constructed according to the German patent application A. 48,553/21g, so that the wires used lie parallel to each other in their whole length, and are covered together, so

that, externally, they have the shape of a band.

If the bifilar winding is so arranged that its capacity is 0.4 to 0.8 of that of the complete loading section, the arrangement can serve for the complete phase-compensation. But even if the self-capacity of the coil is not brought to this comparatively high value, the capacity of the two halves of the coil with respect to each other, which is produced by the bifilar winding, will reduce the variation of the transmission time for different frequencies and exert a favorable effect with regard to disturbing resonant effects. The self-capacity of the coil-halves with respect to each other can, if necessary, also be brought to the most favorable value by special smaller condensers arranged between them.

The bifilar winding is, in fact, the simplest method for creating the capacity relations required for phase-compensation without special condensers in a loading unit. But the fundamental idea of the invention comprises any kind of winding which attains this without special additional condensers.

The bifilar winding itself need not be constructed just according to the simple scheme of Figs. 2 and 3. It will sometimes be advantageous to sub-divide the coil-halves A_1 , B_1 and A_2 , B_2 further, so that the points A_1 and B_1 do not come into close proximity with the points B_2 and A_2 , but with other points of the other half of the coil. It is then possible to give coils of equal self-inductance a different effective self-capacity according to the capacity of the section of the line, and on the other hand, to obtain the same effective self-capacity also for coils of different inductance.

40 The method can in the same sense also be extended to the more or less complete compensation in the case of phantomed lines.

What is claimed is:

45 1. A loading coil for transmission lines having a self-capacity substantially sufficient to compensate for the tendency of the line to produce a greater transmission delay for certain of the message frequencies than for others.

50 2. A loading coil for transmission lines having a self-capacity designed to constitute from four-tenths to eight-tenths of the capacity of an entire section of the transmission line.

55 3. A loading coil for transmission lines having a winding for connection in each side of the line, the wires for the two windings being laid together and wound bifilarly.

60 4. A loading coil for transmission lines having a winding for connection in each side of the line, the wires for the two windings being laid together and wound bifilarly, and the adjacent leads at either end of the coil 65 being connected to line wires extending in

opposite directions and in different sides of the circuit.

In witness whereof, we have hereunto set our hands this 3rd day of May, 1930.

HANS BUSCH.
ALFRED BYK.
